(57) **CLAIM**

The ornamental design for a finger controlled gun safety lock, as shown and described.

DESCRIPTION

FIG. 1 is a left side perspective view of a finger controlled gun safety lock, showing our new design.

FIG. 2 is a left side elevational view thereof; and,

FIG. 3 is a right side elevational view thereof.

The broken lines in the figures illustrate environmental subject matter that form no part of the claimed design.
